UNITED STATES PATENT OFFICE.

CHARLES J. PEMBROKE, OF ROCHESTER, NEW YORK.

PRIMER.

1,207,073.

Specification of Letters Patent.

Patented Dec. 5, 1916.

Application filed June 22, 1914. Serial No. 846,527.

To all whom it may concern:

Be it known that I, CHARLES J. PEMBROKE, a citizen of the United States, residing at Rochester, in the county of Monroe and State of New York, have invented certain new and useful Improvements in Primers, of which the following is a specification.

The object of this invention is to provide 10 a priming device in connection with a carbureter.

In the drawings, Figure 1 is a side elevation of the carbureter, the float feed chamber being shown partly in section, the section being taken on the line 1^x—1^x of Fig. 2. Fig. 2 is a horizontal section through the float feed chamber, the section being taken on the line 2^x—2^x of Fig. 1.

In the drawings like reference numerals 20 indicate like reference characters.

In the drawings, reference numeral 1 indicates a float feed chamber in which is carried a supply of gasoline; 2 an intake through which the gasoline is fed into the 25 carbureter.

3 indicates a compartment in which the needle valve of the carbureter is carried and 4 indicates the casing for the mixing chamber of the carbureter. At the top of the 30 mixing chamber is pivotally mounted a throttle valve 5 operated by a crank 6 to which is connected a link having a section 7 which telescopes in the section 8 and being clamped thereto by a split sleeve at 9.

35 The float chamber of the carbureter is provided with a lateral extension 10 which is shaped to contain gasoline and a valve without interfering with the operation of the float that is contained in the float chamber. Formed in the extension 10 is a valve seat 11 in which is pivotally mounted a valve 12 which valve is surrounded by a stuffing box 13. The valve 12 has a longitudinal opening 14 therein closed by a screw 15. The valve 12 also is provided with 40 the lateral openings 16 and 17 both of which communicate with the longitudinal opening 14. Connected with the lateral opening 16 is a tube 18. In line with the lateral opening 17 is an opening 19 in the valve seat 11. Surrounding this opening 19 is a boss 20 into which is threaded a tube 21 which extends upwardly and communicates with the 45 interior of the mixing chamber of the carbureter above the throttle valve.

The parts are so arranged that when the

valve is in the position shown in full lines in Fig. 1, gasoline can pass up through the tube 18 into the longitudinal opening of the valve 12 and along this opening through the opening 17 and up through the tube 21 into the mixing chamber of the carbureter above the throttle valve. When the valve 12 is given a quarter turn, the tube 18 will assume the dotted line position shown in Fig. 1 and the opening 17 of the valve 12 will be closed against the tube 21.

The operation of my priming device is as follows:

When the engine of the automobile is 70 about to be started, the throttle valve 5 is moved to close the opening at the top of the mixing chamber and the valve 12 is set with the tube 18 in the position shown in Fig. 1. The engine is then turned over once 75 and this will cause the gasoline to be sucked up from the float chamber through the tube 18, valve 12 and tube 21 from which it will be discharged on the throttle valve 5. The valve 12 is then closed. The throttle valve 80 is then opened and as the engine is further rotated, the air will be drawn past the throttle valve 5, which then acts as a baffle from which the gasoline held thereon may be evaporated by the air, enriching the mixture as it passes into the engine. In this manner, a rich mixture is fed into the engine. A stationary baffle may be used to hold the gasoline discharged from the tube 21 in which case the valve 5 would act as a 85 throttle only to produce the suction. The tube 21 may extend down into the gasoline permanently and the valve may be arranged to permit and still regulate the flow through the tube and such a modification is within 90 the scope of my invention.

I claim:

1. In a carbureter the combination of a float chamber and a mixing chamber, a throttle valve in the mixing chamber, a tube 100 extending from the top of the float chamber into the mixing chamber above the throttle valve, a valve at the top of the float chamber opening and closing said tube, said valve having a tubular extension thereon that dips into the gasoline when the valve is open and is raised from the gasoline when the valve is closed.

2. In a carbureter the combination of a float chamber, a tube extending up from 110 said chamber, a valve in said chamber normally closing said tube, a tube on said valve

normally held above the gasolene in the chamber when the valve closes the tube, the end of said tube being immersed in the gasolene when the valve opens said tube.

3. In a carbureter the combination of a float chamber, a tube extending up from said chamber, a valve in said chamber normally closing said tube, a tube on said valve normally held above the gasolene in the chamber when the valve closes the tube, the end of said tube being immersed in the gasolene when the valve opens said tube, a mixing chamber, a throttle valve therein, said tube opening into said mixing chamber above the throttle valve.

4. In a carbureter the combination of a float chamber, a tube extending up from said chamber, a valve in said chamber nor-

mally closing said tube, a tube on said valve normally held above the gasolene in the chamber when the valve closes the tube, the end of said tube being immersed in the gasolene when the valve opens said tube, a mixing chamber, a throttle valve therein, said tube opening into said mixing chamber above the throttle valve, said mixing chamber when closed by the throttle sucking gasolene through the tube 21 and discharging it on the throttle.

In testimony whereof I affix my signature in presence of two witnesses.

CHARLES J. PEMBROKE.
